UNITED STATES PATENT OFFICE.

ADOLPH BONNIOL, OF PROVIDENCE, RHODE ISLAND.

ENGRAVER'S TOOL OR SCRAPER.

SPECIFICATION forming part of Letters Patent No. 366,297, dated July 12, 1887.

Application filed February 16, 1887. Serial No. 227,771. (No model.)

To all whom it may concern:

Be it known that I, ADOLPH BONNIOL, a citizen of France, residing at Providence, in the county of Providence and State of Rhode Island, have invented certain new and useful Improvements in Scrapers; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to that class of engravers' tools known as scrapers, to be used for smoothing off the ragged edge or burr of the lines in an engraver's plate, the object being to provide a cheap, durable, convenient, and useful tool, and one that requires but little grinding to sharpen it.

The invention consists in an improved engraver's tool, and in the arrangements and combinations of parts, substantially as will be hereinafter set forth, and finally embodied in the clauses of the claims.

Referring to the accompanying drawings, in which like letters represent corresponding parts in each of the several figures, Figure 1 is a front view of my improved tool, showing a novel arrangement of cutting-edges therein. Fig. 2 is a transverse vertical section through line α , Fig. 1; and Fig. 3 is a vertical transverse section of a modification.

In said drawings, A indicates the point or forward cutting-edge of the scraper, and has the ordinary configuration shown in similar tools.

B is a side cutting-edge, and is adapted to

take off the feather-edge of engraved lines, &c., left by the etching-needle or other engravers' tool. In some cases it may be more convenient to use the edge C for the same purposes, as in the ordinary scraper.

Said tool is provided with a longitudinal groove, D, having the configuration shown to provide an under-cut edge, as B, and leave a thin edge, as C, so that the same may be easily sharpened, as will be understood. The end E of the tool is drawn down so as to provide a suitable shank, such as is found in ordinary files, &c., to be introduced into a handle.

Said tool may be cast or rolled in shape, or forged or cut from steel without in any way departing from the spirit or scope of my invention.

Having thus fully described my invention, what I claim as new is—

1. As an improved article of manufacture, an engraver's tool or scraper, substantially as herein described, provided with a cutting-edge, A, an edge, B, and an edge, C, substantially as and for the purposes set forth.

2. In an engraver's tool or scraper consisting of a suitable plate of steel having cutting-edges A, B, C, a longitudinal groove, D, and suitable means for attaching said tool to a handle, said parts being arranged and adapted to operate substantially as and for the purposes set forth.

In testimony that I claim the foregoing I have hereunto set my hand this 12th day of February, 1887.

ADOLPH BONNIOL.
